UNITED STATES PATENT OFFICE.

GEORGE BURDER THAYER, OF BOSTON, MASSACHUSETTS, ASSIGNOR TO
HIMSELF AND GEORGE H. WOOD.

ELEVATOR.

SPECIFICATION forming part of Letters Patent No. 283,881, dated August 28, 1883.

Application filed May 17, 1883. (No model.)

To all whom it may concern:

Be it known that I, GEORGE BURDER THAYER, a citizen of the United States, residing at Boston, in the county of Suffolk and 5 State of Massachusetts, have invented certain new and useful Improvements in Elevators; and I do hereby declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 This invention relates to means for doing away with much of the complicated and expensive machinery now employed to operate power-elevators, as well as to obviate the abrupt and jerky motions now so common in 20 this class of elevators.

My invention consists in certain details of mechanical construction, as hereinafter explained.

The drawings accompanying this specification represent, in Figure 1, a vertical section, 25 and in Fig. 2 an elevation, of an elevator containing my improvements.

In these drawings, Figs. 1 and 2, A represents the frame of the structure or the corner- 30 posts of the well, which consists of upright beams B B B B, which constitute the guides of the car. The car is shown in this instance as adapted to freight purposes, and composed simply of a platform, D, upright corner-posts

35 E E E E, spanned at top by horizontal rails F F' F'. Upon opposite top rails, F' F', of the car I secure standards G G, and in these standards I journal the ends of a shaft, H, and to these ends of said shaft H, I secure twin wheels 40 I I', grooved in their peripheries. The wheels I I' may be pivoted directly to the rails F F' and the shaft H omitted. Upon the framework of the elevator-shaft, adjacent to the wheels I I' above named, I dispose a counter-

45 weight frame, J J, of usual form, which slides upon vertical ways a a, secured to the adjacent corner-beams, B B, these frames carrying adjustable weights b b in such number and of such weight as may be deemed necessary in 50 each instance. Upon the top of each frame J J,

I erect standards e e, and in each of these standards I pivot a grooved wheel, d or d'. Upon opposite sides of the top of the frame A, and over the wheels I d I' d', respectively, I erect standards K K, in which I journal the ends of 55 a horizontal shaft, L, one journal of this shaft carrying the usual pulleys, by which it is put in rotation in one or the other direction. Upon each end of the shaft L, and over and in alignment with the wheels I d I' d', respectively, I 60 secure pulleys e e', each of which has two peripheral grooves, f f', of differential diameters.

M M' represent two endless ropes, which constitute the hoisting-ropes of the car, one 65 being employed to each set of wheels and pulleys, and led about such wheels and pulleys, as follows, taking as a starting-point the * shown on one pulley, e, in Fig. 1 of the drawings: From this point * the rope on each side 70 of the structure passes down, as shown by the numeral 10, (on the side denoted by the numeral 20,) to and about the wheel d, thence upward on the opposite side, as shown by numeral 11, to and about the lesser groove f', 75 thence downward on the same side as at first, as shown by numeral 12, to and about the wheel I', thence upward on the opposite side the latter, as shown by numeral 13, to and about the larger pulley e, thus completing the 80 round of the rope.

The operation of this device is as follows: Supposing the driving-shaft L to be in rotation in the direction of its arrow in Fig. 1, the side 13 of each rope is winding up on the 85 groove f of large diameter with a tendency to raise the car, while at the same time that this motion of the car is taking place the part 10 of the opposite side of the rope is unwinding from the smaller groove f' about the wheel d, 90 and the part 11 of the rope upon the same side as part 13 is winding upon the said groove f', to lower the counter-weight at the same rate of speed as the ascending car. Simultaneously with the above movements the part 12 95 of the rope is unwinding from the smaller groove f' about the wheel I', the result being that the car travels at a rate of speed equal to the mean between the circumference of the grooves f f'. Rotation of the pulleys e e' in the 100

opposite direction actuates the car in the opposite direction—that is, the car is lowered while the counter-weights rise, as will be readily understood. It will be seen from this that the speed of the car is determined by the difference in diameter of the pulleys $e e'$, since the wheels I and d are practically mere anti-friction rollers and bearings to permit of the movements of the rope. The discrepancy between the speeds, due to the differential diameters of the pulleys $e e'$, determines the rate at which the car travels. The greater the discrepancy in the diameters of the pulleys of each pair the greater the speed of the car, and vice versa.

The weighted frames perform two functions. They serve to counterbalance the car, and, in conjunction with the weight of the car, to cause friction between the rope and the pulleys $e e'$, to prevent slipping of such rope. In setting up an elevator under my plan the car and counter-weight frames are to be loaded to produce friction upon the rope, according to the desired lifting capacity of such car.

In Figs. 3 and 4 of the drawings I have shown an alternative construction of my elevator. In this instance I duplicate the pulleys $e e' e' e'$ of Figs. 1 and 2, placing them at the bottom of the structure as well as at the top, these duplicate pulleys being shown in said Figs. 3 and 4 at $e^2 e^2 e^3 e^3$. In this modification I dispense with the counter-weights and their sliding carriages and secure the two pairs of idler-rolls to a single shaft, N , journaled in bearings in the top of the car, these pairs of wheels being shown at $I^2 I^2 I^3 I^3$. The shaft N is not essential. It may be omitted and the wheels pivoted to the top of the car. To exert the requisite friction upon the hoisting-rope in this modified construction, I mount the journals of the shafts P or the pivots of the wheels $I^2 I^2 I^3 I^3$ of the lower pulleys, $e^2 e^2 e^3 e^3$, in twin levers $Q Q$, disposed at the lower part of the well, and upon opposite sides of the car, these levers being pivoted, as shown at g , to central posts, $h h$, in the elevator-well. The tails of the levers $Q Q$ are weighted according to the intended capacity of the car.

The construction of an elevator under my plan, as hereinbefore described, does away with much of the comparatively complicated machinery now employed for the purpose, thereby reducing the power required to operate the elevator, as well as lessening the cost of the latter. The motion of the car is smooth and easy, the abrupt jerky movements frequently observed in elevators as heretofore constructed being entirely avoided.

My object in employing duplicate sets of pulleys and hoisting-ropes, arranged one upon each side the car, as shown, is to equalize the draft upon the latter and prevent fall of such car in the event of one of the ropes giving out. Any other additional safety device may be used.

In lieu of pivoting the idler-wheels to the car and counter-weights, as shown in Figs. 1 and 2 of the drawings, or jointly to the car, as shown in Figs. 3 and 4, the said idler-wheels may be pivoted jointly to a carriage adapted to slide upon guides secured to upright posts at one side of the elevator-well, while the differential pulleys are pivoted to the top and bottom of the well, the hoist-rope being secured at one end to this carriage, thence passing upward about a sheave and secured at its opposite end to the car; or this last-described rope system may be located in the well above the highest point reached by the car, the differential groove-wheels being journaled in suitable supports and the carrier of the idler-wheels traversing horizontal guides.

I claim—

1. In combination with an elevator-carriage and a counterbalance-weight, a differential pulley on the driving-shaft, and an endless suspending rope or chain which passes around the grooves of said pulley and around pulleys attached to said elevator-carriage and weight, substantially as set forth.

2. As the operating mechanism of an elevator-car provided with a counter-weight, an endless traveling rope passing over the two grooves of a differential pulley or sheave, one bight of the rope being connected with the car, the other with the counter-weight.

3. As the operating mechanism of an elevator-car, an endless traveling rope passing over the two grooves of a differential pulley, (or around the two parts of a differential welloass or drum,) the two bights of the rope passing around the moving point of the system, in combination with a second stationary differential pulley similar to the first mentioned, or its equivalent, and suitable means for keeping a tension upon the rope proportional to the desired load.

In testimony whereof I affix my signature in presence of two witnesses.

GEORGE BURDER THAYER.
